UNITED STATES PATENT OFFICE.

CHARLES H. BUSCH, OF KENOSHA, WISCONSIN, ASSIGNOR TO SIMMONS COMPANY, OF KENOSHA, WISCONSIN, A CORPORATION OF DELAWARE.

FURNITURE.

Application filed February 24, 1921. Serial No. 447,391.

This invention relates to the manufacture of metal furniture but more particularly to the construction of legs or supports for beds, tables, chairs and other similar articles, and 5 has for its primary object to provide a construction which combines lightness, strength and durability with an artistic and attractive appearance.

Another object of the invention is to 10 enable the reproducing in thin metal of designs having the appearance of turned wood.

The many other objects and advantages 15 of the invention will be better understood by reference to the following specification when considered in connection with the accompanying drawing illustrating a selected embodiment thereof, in which:—

Fig. 1 is an elevation partially in section; 20 Fig. 2 is a section on the line 2—2 of Fig. 1; and

Fig. 3 is an elevation on a reduced scale of the invention applied to a bed.

Referring to the drawings, it will be seen 25 that the leg 4 comprises an outer or ornamental shell 5 and an inner or supporting tubular shell or stem 6. The frame 7 of the bed or other article of furniture is provided with downwardly projecting tubular 30 members or posts 8 open at the end to receive and closely fit about the leg. The inner stem 6 is substantially uniform in cross section to provide the maximum supporting strength and if desired may be of slightly 35 heavier metal than the outer shell.

The outer shell 5, which in the form 40 shown, is stamped from a single flat blank, may be of any suitable pattern. A thin stamped shell of this nature would be very liable to collapse or bend when supporting any considerable weight, and it would be impracticable to form such a shell of metal of sufficient thickness to secure the necessary rigidity and strength. This shell is 45 preferably completely formed in the selected design before the inner or weight carrying stem is inserted.

A spacing ring 9 is inserted between the inner stem and the outer shell. The annular 50 flange 10 of this ring presses against the outer face of the inner stem. Another spacing ring or cap 11 is inserted between the shells, and this ring projects inwardly over the top of the inner stem in the manner 55 shown. An annular flange 12 on this ring

11 fits within the rim of the inner shell. These rings firmly support the stem and shell at two spaced points so that the relative position thereof is maintained. The upper rim 13 of the outer shell is turned inwardly over the ring 11 after the ring is in position.

The depending tubular members or posts 8 rest on the shoulder formed by the bead 14 on the outer shell. The weight of the 65 bed or other article of furniture is transmitted from the post 8 to the inner stem 6 through the portion 15 of the outer shell, the inwardly turned rim 13, and the ring 11, forming a hanger. The ornamental portion 70 of the outer shell is not required to carry any of the weight of the bed.

A bead 16 is preferably formed in the contracted lower portion of the shell 5. The stem 6 is preferably slightly contracted at 75 17 to fit within the corresponding lower portion of the outer shell. When the inner stem has been fully inserted within the outer shell, a bead 18 is spun on this inner stem to fit within the corresponding bead 16 80 in the outer shell and thus firmly lock these parts together near the base of the leg. The caster 19 is provided with a protuberance 20 which fits within the lower portion of the leg, and a cap 21 fitting over the end of the 85 leg and forming a closure for the opening therein.

It will be readily evident that with the construction forming the present invention a substantial and durable form of furniture 90 is provided. The parts may be made of steel and any suitable finish may be applied upon the outer shell. As no weight is carried by the ornamental portion of the outer shell, this shell may be constructed of very thin metal which may be readily pressed, spun or otherwise shaped into the selected 95 design. The finished bed has none of the crude appearance of the usual cast iron beds and is much lighter in weight. The parts of the leg are so formed and interlocked that they will not become loose and rattle. The leg is separable from the main frame of the bed or other article of furniture. This not only facilitates construction but 100 greatly simplifies the handling and shipping of the finished product.

I am aware that many changes may be made in the construction and arrangement of parts without departing from the spirit 110

of my invention, and I reserve the right to make all such as fairly fall within the scope of the following claims.

I claim:

5. 1. In an article of furniture, a supporting leg comprising an inner stem and an outer metallic shell having an interlocking connection between their upper ends comprising an inturned flange on said outer shell and a cap 10 on said inner stem, said cap engaging the top of said inner stem and the under side of said inturned flange.

2. In an article of furniture, a main frame provided with depending posts open at the 15 base, and leg members insertible in said posts and each comprising a supporting stem, an ornamental shell about said stem having its upper end fitting within the base of the post, and means disposed at intervals along the 20 axis of said stem for relatively positioning said shell and said stem.

3. In an article of furniture, a main frame provided with sockets therein, and supporting legs for said frame insertible into said 25 sockets and comprising an inner substantially cylindrical shell, an outer ornamental shell fitting said socket, and spaced positioning members disposed between said shells.

4. In an article of furniture, a frame provided with depending posts open at the base, leg members insertible in said posts and each comprising an inner stem and an outer shell, and means forming an interlocking connection between the tops of the stem and shell, the outer shell having a shoulder formed thereon to engage and support the 35 base of the corresponding post.

5. An article of furniture comprising a frame including depending posts each having a socket formed in the base thereof, and supporting legs therefor insertible in said 40 sockets, said legs comprising an outer shell and an inner supporting stem and each provided with a shoulder formed on the outer shell adjacent to the upper extremity thereof to co-act with the base of the corresponding post.

6. In an article of furniture, a frame provided with a depending post open at the 45 base, a supporting leg member insertible in

said post, and an annular sheet metal member acting between the upper end of said leg member and the lower end of said post to cause said post to be supported by said leg member.

7. In an article of furniture, a frame provided with a depending post open at the base, and a leg insertible into said base and comprising an inner stem and an outer shell, the upper end portion of the outer shell forming a hanger coacting with the upper end portion of the inner stem and the lower end of the post to cause said post to be supported by said inner stem.

8. In an article of furniture, the combination of a supporting post having a socket in its lower end, a leg for said post comprising an inner stem of considerably smaller cross sectional size than said socket, a sleeve surrounding said stem and having its upper end portion of considerably larger cross sectional size than the stem and adapted to snugly fit within said socket, and the portion of said shell below said upper end portion being shaped so as to serve as an ornament for the exposed portion of the leg, means for effecting interlocking engagement between the upper ends of said stem and shell, and means for seating the lower end of said post on said shell above the ornamental portion thereof.

9. In an article of furniture, the combination of a supporting post provided with a socket in its lower end, a leg for supporting said post and comprising an inner stem of considerably smaller cross sectional size than the socket end of said post, an outer shell of relatively thin material extending over substantially the entire length of said stem and having its upper end portion spaced from said stem and adapted to snugly fit within said socket, the portion of said shell below said upper end being shaped so as to serve as an ornament for said stem, and means for transferring the load of said supporting post from said shell to said stem so that the ornamental portion of the shell is relieved from bearing any substantial load.

CHARLES H. BUSCH.
